UNITED STATES PATENT OFFICE.

WILLIAM W. DUDLEY, OF LANCASTER, PENNSYLVANIA.

DESIGN FOR A WATCH MOVEMENT FRAME.

Application filed October 2, 1922. Serial No. 3,864. Term of patent 14 years.

To all whom it may concern:

Be it known that I, WILLIAM W. DUDLEY, residing at Lancaster, Pennsylvania, a citizen of the United States, have invented a new, original, and ornamental Design for Watch-Movement Frame, of which the following is a specification.

Referring to the drawing which forms a part of this specification, the figure is a plan view of a watch movement frame showing my new design.

Ordinarily the watch case has a back or

cover of glass which discloses the design although sometimes the cover or back is hinged or otherwise openable so that the design may be seen.

I claim:

The ornamental design for a watch movement frame.

In testimony whereof I hereunto affix my signature.

WILLIAM W. DUDLEY.

Witness:

CLIFFORD W. DUDLEY.
